UNITED STATES PATENT OFFICE.

MOSES SPENCER, OF SAYLESVILLE, RHODE ISLAND, ASSIGNOR, BY MESNE ASSIGNMENTS, TO HOPEDALE MANUFACTURING COMPANY, OF MILFORD, MASSACHUSETTS, A CORPORATION OF MASSACHUSETTS.

SPINNING FRAME.

Application filed November 15, 1917. Serial No. 202,098.

To all whom it may concern:

Be it known that I, Moses SPENCER, a citizen of the United States, residing at Saylesville, in the county of Providence and State of Rhode Island, have invented certain new and useful Improvements in Spinning Frames; and I do hereby declare the following to be a full, clear, and exact description of the invention, such as will enable others skilled in the art to which it appertains to make and use the same.

The present invention relates to an improvement in spinning frames, and more particularly the invention relates to an improvement in bunch-building mechanisms.

The object of the invention is to improve and simplify the construction of bunch-building mechanisms in order that these mechanisms and devices may perform their respective functions more efficiently. To the accomplishment of this object and such other objects as shall hereinafter appear, the invention consists in the improved spinning frame described and particularly pointed out in the following specification.

In the accompanying drawings illustrating the preferred form in which it is contemplated embodying the invention, Figure 1 is a front elevation of a portion of a spinning frame showing the application thereto of the bunch-building mechanism; Fig. 2 is an enlarged view of the butt end of a bobbin showing the preliminary bunch as spun thereon by the bunch-building mechanism; Fig. 3 is a side elevation on an enlarged scale of a part of the bunch-building mechanism and adjacent parts of the spinning frame; Fig. 4 is a plan of the parts shown in Fig. 3; and Fig. 5 is a detail of the cam gear showing it in a different position.

In its general features of construction, the spinning frame to which the improved bunch-building mechanism is applied, may be of any usual or preferred form and may be used for the spinning of woolen or cotton yarns. The spinning frame illustrated in the drawings comprises a spindle rail 9 secured to the frame 10 of the machine. Mounted on the spindle rail 9 are the spindles 11 which carry the bobbins 12, upon which the yarn 13 is spun. The laying of successive layers of yarn upon the bobbins is effected by the up and down traverse of the

lifter rail 14 supported on the lifter rods 15. The yarn is fed from the spinning rolls 17 and is properly laid on the bobbins by means of caps or covers 18. The up and down traverse of the lifter rail and its successive movements downward as the successive layers of yarn approach the tip of the bobbins are communicated to it by a carriage 20 provided with tracks 21 which rest on rolls or wheels 22 journaled in a bracket 23 fastened to the frame of the machine.

At the beginning of the spinning operation the carriage 20 makes its regular reciprocatory motion at the limit of its rightward movement, as shown in Fig. 1, thereby holding the lifter rail 14 raised in order that the butt of the bobbins may be spun first. Throughout the spinning operation the carriage progressively approaches the limit of its leftward movement, thereby permitting the lifter rail and bobbins to progressively descend. The movements of the carriage 20 to the right, as viewed in Fig. 1, in order to raise the lifter rail, are imparted by a heart-shaped cam 25 mounted on the end of a rotating shaft 26. The cam 25 engages a cam roll 27 carried by an oscillatory arm 28 pivoted at 29 on a block 24 adjustably secured on the machine frame. The side 30 of the lower end of the arm 28 engages a roll 32 pivoted on a block 33 adjustable vertically on a lever 34 fulcrumed at 35 on a bracket 36. The upper end 38 of the lever 34 is guided in its oscillatory movements by an arc-shaped plate or guide 39. The lever 34 carries an internally-threaded nut 40 which receives a worm 41 formed on a shaft 42 journaled in the machine frame. The headed end 43 of the worm 41 loosely engages a block 44 fixed on the carriage 20. The oscillatory movements of the lever 34 caused by the rotation of the heart-shaped cam, imparts a reciprocatory motion to the shaft 42 and the carriage 20, the connections between the lever 34 and the nut 40 being such as to permit the necessary relative motion between the two. The carriage 20 is connected with the left-hand lifter rod 15 by means of a chain 46, the lower end of which is fastened to a collar 47 adjustably secured to the lower end of the lifter rod. The chain 46 passes over an idler 48 pivoted on the bracket 23. The downward traverse

of the carriage 20 is 100 connected with the left-hand lifter rod 15 by means of a chain 46, the lower end of which is fastened to a collar 47 adjustably secured to the lower end of the lifter rod. The chain 46 passes over an idler 48 pivoted on the bracket 23. The downward traverse

of the lifter rail 14 and the movement of the carriage 20 to the left are effected by gravity.

In order that the reciprocations of the carriage may be progressively to the left so that the lifter rail and bobbins may be progressively lowered, the shaft 42 is intermittently turned by a gear 50 loosely mounted on the shaft 42 and in key and key-way connection therewith. The gear 50 is driven by a gear 51 which in turn is driven from a suitable source of power.

The building of the preliminary bunch 54 on the butt end of the bobbins is effected by holding the carriage 20 substantially stationary at the limit of its rightward movement, for a predetermined length of time at the beginning of the spinning operation. This is accomplished by the bunch-building mechanism which comprises a lever 55 pivoted at 56 and having a hooked end which is adapted at the proper time to engage a stop lug 58 secured to the carriage 20. The engagement of the hooked lever 55 with the stop lug 58 prevents the leftward movement of the carriage, thereby permitting the bunch to be built on the butt end of the bobbins. It will be understood that the engagement of the hook 55 with the stop lug 58 does not absolutely prevent all movement of the carriage 20, but that the latter will have a slight movement as the tip of the heart-shaped cam 25 passes the cam roll 27. This slight movement of the carriage is sufficient to impart a small vertical traverse to the lifter rail, and consequently the preliminary winding or bunch will not be built up on one point, but will be distributed over a short length of the butt, as shown in Fig. 2.

The hook 55 is lowered into engagement with the stop lug 58, at the beginning of the spinning operation, by the clockwise oscillation of a bellcrank lever 59 pivoted at 60 on the machine frame. The lever 59 is connected with the hook 55 by a spring 61, so that if the bellcrank is actuated to lift the hook 55 while the carriage is attempting to move toward the left, a straining of the parts will not ensue. The bellcrank lever 59 is connected by means of a link 62 with a lever 63, which carries a cam roll 64 arranged to travel in a cam path 65 grooved in the web of a cam which is formed as a mutilated or interrupted gear 67 pivoted on a stud 68 secured to a bracket 69 fastened to the end of the spinning frame. During the regular spinning operation, the cam gear or cam 67 is maintained in the position shown in Fig. 4, which may be called its normal or inoperative position, and the hook 55 is thereby held raised; but during the building of the preliminary bunch the cam gear 67 is in its operative position as shown in Fig. 5, with its cam groove in such position that the link 62 is moved to the right (as viewed in Fig. 1)

to permit the hook 55 to be lowered into the path of the stop lug 58. The cam gear 67 is turned into the position of Fig. 4 by a pinion 71 loosely mounted on the lower end of a vertically disposed shaft 72, which rotates constantly in the direction indicated by the arrow in Fig. 4 and is driven by a constantly rotating worm 73. The driving connection between the shaft 72 and the pinion 71 consists of a collar 74 loosely mounted on the shaft 72 and in key and key-way connection therewith. The lower end of the collar 74 is provided with ratchet teeth which are adapted to mesh with corresponding teeth on the pinion. When the cam gear 67 has been turned into the position of Fig. 4, it is held therein by the engagement of a wedge-shaped stop lug 76 secured to the cam gear, with a stop lever 77 pivoted at 78 on an upward extension of the stud 68. A contraction spring 79 tends to hold the stop lever downward in the position shown in Fig. 3, and the collar 74 in mesh with the pinion 71.

At the beginning of the spinning operation when the preliminary bunch is to be built, the collar 74 is disconnected from the pinion 71 and the stop lever is raised and disengaged from the stop lug 76. Thereupon a spring 81, fastened at one end to the bracket 69 and at the other end to a strap 82 which is wrapped around and secured to the hub of the cam gear 67, acts to turn the cam gear into its operative position, as shown in Fig. 5. The amount of rotation of the cam gear, which is determined by the length of time the hook 55 is to engage the stop 58, which in turn is determined by the amount of yarn necessary to constitute the preliminary bunch, is limited by an adjustable stop 83 which, as the cam gear turns, is brought up against the cam roll 64. The collar 74 is disengaged from the pinion 71 and the stop lever 77 is raised by means of a lever 84 pivoted at 85 on a stud 86 rising from the bracket 69. The free end of the lever 84 is bifurcated and is provided with inturned bosses which engage a groove in the collar 74. A pin 87 fixed in the lever 84 loosely engages a vertical slot 88 in the free end of the stop lever 77. This slot 88 permits the stop lever to rise without disengaging the collar 74 from the pinion 71, when the gear 67 is being turned into inoperative position and the wedge-shaped stop lug 76 passes under the stop lever 77. The outer end of the lever 84 is articulated by means of a link 90 with a hand lever 91 pivoted at 92 on the machine frame. The lever 91 is manipulated by the operator, in order to disconnect the collar 74 from the pinion 71 and to raise the stop lever 77 by means of a handle 93. The handle 93 is integral with the arm 94 of the hand lever 91. This arm 94 is curved at 95 to fit a groove 96 in the hub of the gear 50; the

gear 50 is thus prevented from axial movement with the shaft 42 during the regular spinning operation.

The building of the preliminary bunch on the butt end of the bobbins is necessarily performed at the beginning of the spinning operation by reason of the construction and arrangement of the parts of the spinning frame. The progressive movements of the carriage toward the left (as viewed in Fig. 1) as the spinning proceeds, leaves the carriage substantially at the limit of its leftward movement at the completion of the spinning operation. Before the spinning of the next set of bobbins can be commenced, it will be necessary for the operator to return the carriage to its initial position, that is, to the limit of its rightward movement. This he does by turning the hand wheel 97 fixed on the outer end of the shaft 42. Before the shaft 42 can be rotated, however, the gear 50 must be disconnected from the gear 51, and before this can be done, the operator must disengage the hand lever 91 from the groove in the gear 50. In doing so, he oscillates the lever 84, thereby disconnecting the collar 74 from the pinion 71 and raising the stop lever 77. Thereupon the spring 81 acts to turn the cam gear 67 into operative position, by which movement the bellcrank 59 is oscillated in a clockwise direction and the hook 55 is lowered into the path of the stop lug 58. It is thus seen that the preliminary bunch building is necessarily incident to the spinning operation.

The amount of yarn constituting the preliminary bunch is dependent upon the length of time the hook 55 is in engagement with the stop lug 58, and this in turn is dependent upon the rate of rotation of the shaft 72 and the adjustment of the stop 83. Before the operator restarts the spinning frame in operation, he must slide the gear 50 into mesh with the gear 51. Having done so he releases the handle 93, and thereupon the spring 79 slides the collar 74 into mesh with the pinion and depresses the stop lever 77 into operative position. Incidentally, the curved part 95 of the arm 94 is inserted in the groove 96. The rotation of the pinion 71 now turns the cam gear 67 from the position of Fig. 5 to that of Fig. 4. It will be seen that the nearer the stop 83 is set to the active part 98 of the cam path 65, the shorter time the hook 55 will be in engagement with the stop 58.

The stopping devices for automatically stopping the spinning frame upon the completion of the spinning operation, comprise a bellcrank lever 100, by the oscillation of which in a clockwise direction the shipper 101 is actuated to shift the belt 102 from the fast pulley 103 to the loose pulley 104. The bellcrank lever 100 is oscillated by a lever 106 pivoted on an upright 107 fixed on the block

44. The free end of the lever 106 is provided with a notch 108 which is adapted to fit over the end 109 of the bellcrank 100 when the carriage 20 has reached the extreme of its leftward movement. The next succeeding movement of the carriage to the right oscillates the bellcrank 100. The arm 110 of the bellcrank 100 is connected with the lower end of an obliquely disposed rod 111, the upper end of which is slidingly received in a guide 112 on a bracket 113. The free upper end of the rod terminates below a horizontally disposed shipper rod 114, the outer end of which is loosely received in a slot 115 in the bracket 113. During the spinning operation the outer end of the shipper rod is depressed and a notch 116 therein engages the lower end of the slot 115. But when the bellcrank 100 is oscillated at the completion of the spinning operation, the rod 111 is raised and brought up against the shipper rod; the notch 116 of the latter is thereby disconnected from the bracket 113, and thereupon a spring 118 acts to draw the shipper rod 114 to the right (as viewed in Fig. 1). The movement of the shipper rod to the right, actuates the shipper 101 with which the rod 114 is connected by the arm 119, the bar 120 and the arm 121. The actuation of the shipper 101, as before described, shifts the belt 102 from the fast pulley 103 to the loose pulley 104 and stops the machine.

The objects of the present invention have been pointed out and a specific form of mechanism has been illustrated and described for carrying out these objects. It will be understood, however, that the invention is not limited to the specific form shown and described, but may be embodied in other forms without departing from the spirit of the following claims.

Having thus described the invention, what is claimed is:—

1. A spinning frame having, in combination, spinning devices including a reciprocating carriage, and a bunch-building device comprising a cam, a rotating shaft, connections between the two whereby the former may be turned into inoperative position by the latter, means for turning the cam into operative position, means under the control of the operator and adapted to be brought into operation when the operator restarts the spinning operation for disconnecting the shaft from the cam to permit the latter to be turned into its operative position, connections between the cam and the reciprocating carriage for limiting the movement of the carriage for a predetermined length of time to produce a relatively short traverse, and means for reconnecting the shaft with the cam to permit the carriage to resume its reciprocations.

2. A spinning frame having, in combination, spinning devices including a recipro-

- 4
- cating carriage, and a bunch-building device comprising a cam, connections between the cam and the carriage adapted to limit the movement of the latter for a predetermined length of time at the beginning of the spinning operation to produce a relatively short traverse, and means for turning the cam into operative position and for thereafter returning it to inoperative position, said 10 means comprising a rotating shaft and means under the control of the operator for disconnecting the shaft from the cam and for thereafter operatively connecting the shaft with the cam.
- 15 3. A spinning frame having, in combination, spinning devices including a reciprocating carriage, and a bunch-building device comprising a cam, a rotating shaft, connections between the shaft and the cam adapted to turn the latter into inoperative position, means for turning the cam into operative position, and means under the control of the operator for disconnecting the shaft from the cam to permit it to be turned 25 to operative position, and connections between the cam and the reciprocating carriage.
4. A spinning frame having, in combination, spinning devices, and a bunch building mechanism comprising a rotating shaft, a gear loosely mounted thereon and having provision whereby it may be rotated by the shaft, a second gear adapted to be actuated by the first gear, and means cooperating 35 with the second gear and with the spinning devices whereby the vertical movement of the latter may be limited at the beginning of the spinning operation.
5. A spinning frame having, in combination, spinning devices including a reciprocating carriage, and a bunch-building device comprising a rotating shaft, a cam, operative connections between the cam and the reciprocating carriage adapted to limit the movement of the latter at the beginning of the spinning operation when the cam is in operative position to produce a relatively short traverse, means for turning the cam 45 into operative position, and means connect- 50 ed with the shaft for returning the cam to inoperative position.
6. A spinning frame having, in combination, spinning devices including a reciprocating carriage, and a bunch-building device comprising a cam, means actuated by the cam and cooperating with the carriage adapted to limit the movements of the carriage when the cam is in operative position to produce a relatively short traverse, and means under the control of the operator for turning the cam into operative position when the operator restarts the spinning operation. 55
7. A spinning frame having, in combination, spinning devices including a reciprocating carriage, and a bunch-building device comprising a cam, means actuated by the cam and cooperating with the carriage adapted to limit the movement of the latter for a predetermined length of time at the beginning of the spinning operation when the cam is in operative position to produce a relatively short traverse, and means under the control of the operator for turning the cam into operative position and for there- 70 after returning it to inoperative position. 75
8. A spinning frame having, in combination, spinning devices and a bunch building mechanism comprising means for imparting a normal traverse to the spinning devices including a cam for moving the spinning devices in one direction, and a hook for limiting the return movement of the spinning devices to thereby impart to the spinning devices traverses of relatively short extent 80 upon successive revolutions of the cam. 85
9. A spinning frame having, in combination, spinning devices, actuating means for imparting a normal traverse thereto, and a hook for limiting the return movement of the spinning devices during each traverse thereof to thereby cause said actuating means to impart to the spinning devices traverses of relatively short extent. 90

MOSES SPENCER.
